CAN OPENER

Filed Dec. 15, 1924

UNITED STATES PATENT OFFICE.

ALFRED PAGE, OF BERKELEY, CALIFORNIA.

CAN OPENER.

Application filed December 15, 1924. Serial No. 756,010.

This invention relates to hand operated can openers principally for round cans and has for its object the provision of means whereby the can need not be held during the cutting operation, and wherein both hands of the operator are used to manipulate the device thus bringing more power to bear on the operation, and resulting in much greater speed than with other openers of this type, yet withal a simple, durable construction adapted to sell for a small price.

My improved can opener is shown in the drawings accompanying this application, and in Figure 1 is shown in plan in position on a large can ready to start the cut, and in Figure 2 the inner ends of the levers only are shown with knives contracted to cut a much smaller can.

Figure 3 is an elevation of the fixed blade on the ends of the levers as seen in direction of the arrow 3, and Figure 4 is a side elevation of the adjustable blade of each lever as seen from the line IV-IV of Figure 1.

Figure 5 is a sectional elevation of the adjustable lever joint.

Briefly described my can opener comprises a pair of levers 1 and 1' adjustably pivoted together in slots 2, 2' and each carrying fixed blades 3, 3' at one end and formed into suitable handle grips 4, 4' at the other end.

Each lever also carries a slidable blade 5, 5' which may be slid along the levers so that all four blades may be pushed through the end of the can when placed in the position shown in Figure 1 and after which the handle ends 4, 4' are simply pulled toward one another until the four blades projecting through the can each make a quarter revolution until they stop by abutting one another and the end of the can is cut off.

As the handles come together in finishing the cut they are preferably offset as shown so that the grip does not have to be changed while operating the device.

The blades are pointed as shown in Figure 3 and each provided with a small spur 6 struck out of the side of the blade and the function of which is to engage under the tin of the can when the blade is pushed through so as to prevent the blade backing out until the cut is finished, as shown in

Figure 4. The sliding blades 5, 5' are formed to slidably embrace the levers as shown and the metal of the sliding portion is also struck up to form a small lug 7 to insure the cutter blade remaining adjacent the can edge in cutting and not crawling inward as with some cutters. Also the blades are preferably slightly crowned on their outer surfaces and sharpened outwardly from the inner side as indicated at 8 in Figure 1 so that the blades will normally be carried outward against the side of the can.

To facilitate adjusting the levers in their slotted engagement to different sizes of cans, I preferably provide teeth 9 along one edge only of each slot and a rivet pin in the form of a small pinion 10 engaging the teeth and having a plate 11 riveted at each end to hold the assembled levers together, thus, when the levers are pushed in or out to adjust them the pivotal point is always the proper distance from the end blades 3 and 3' to fall over the center of the can when the sliding blades 5, 5' are adjusted to the proper position for the particular can.

By thus providing a pair of levers pulled together by the force of both arms and retaining the blades in place by means of the lugs 6 and 7 it is not necessary to hold the can at all and the can top may be cut out in the quickest space of time with the very minimum of labor.

I claim:

1. A can opener comprising a pair of levers pivoted to one another, two blades on each lever adapted all to penetrate the end of a can and to cut around the edge of the end upon pivotally operating the levers.

2. A can opener comprising a pair of levers pivoted to one another, two blades on each lever adapted all to penetrate the end of a can and to cut around the edge of the end upon pivotally operating the levers, said levers having sliding adjustment on the pivot.

3. A can opener comprising a pair of levers pivoted to one another, two blades on each lever adapted all to penetrate the end of a can and to cut around the edge of the end upon pivotally operating the levers, said levers having sliding adjustment on the pivot, and the pivot being in the form of a pinion and engaging teeth on opposite sides

respectively of a slot formed in each lever whereby the levers are geared together in their adjustment.

4. A can opener comprising a pair of levers pivoted to one another, two blades on each lever adapted all to penetrate the end of a can and to cut around the edge of the

end upon pivotally operating the levers, said levers having offset handles adapting the levers to be revolved on their pivotal connection to bring the blades of opposite levers substantially in abutting relation. 10
